UNITED STATES PATENT OFFICE.

EDWARD S. MORRIS, OF LOS ANGELES, CALIFORNIA.

DESIGN FOR A FURNITURE PEDESTAL.

Application filed October 6, 1924. Serial No. 10,971. Term of patent 7 years.

To all whom it may concern:

Be it known that I, EDWARD S. MORRIS, a citizen of the United States, residing at Los Angeles, in the county of Los Angeles and State of California, have invented a new, original, and ornamental Design for Furniture Pedestal, of which the following is a specification, reference being had to the accompanying drawing, forming a part thereof.

In the drawing, Fig. 1 is an elevation showing the pedestal and illustrating in dotted lines its usual or typical use as a pedestal for supporting a mirror, and Fig. 2 is an enlarged top plan of the pedestal.

I claim:

The ornamental design for a furniture pedestal, as illustrated.

EDWARD S. MORRIS.
